SLIP RING ASSEMBLY

Joseph P. Madden, Parma, Ohio, assignor to The Cleveland Electric Motor Company, Cleveland, Ohio, a corporation of Ohio

Application May 11, 1949, Serial No. 92,649

6 Claims. (Cl. 171—322)

1

This invention relates to a dynamoelectric machine having provision for effectively transmitting air between the outboard end of the rotor and the interior of the machine along a path passing through the slip-ring assembly and, more particularly, to a molded slip-ring assembly by means of which this may be accomplished.

In the past, slip-ring assemblies have in some instances been made of a molded material such as a synthetic resin; however, such slip-ring assemblies have in general been subject to the defect that the development in the assembly of high temperatures, such, for example, as temperatures in the neighborhood of 400° Fahrenheit, tends to bring about break-down, especially under the influence of the electrical conditions obtaining in the immediate vicinity of the slip-rings and the conductors leading from them. For this reason, there has been a tendency to avoid the use of an integrally molded core, notwithstanding its advantages, in favor of a core made up of several distinct parts, each separately molded, the theory being that in the event of break-down one or more of such separately molded parts can be replaced and the assembly as a whole returned to operation. This, however, has given rise to the possibility of separation between the several parts and attendant misalignment of the slip-rings, with consequent "jumping" of the brushes; so that no wholly satisfactory solution has heretofore been found to the problem of making up a unitary slip-ring assembly embodying a molded core.

Other defects have been found to reside in or to follow from the difficulties experienced by the molder in controlling as accurately as required the relative location of the slip-rings and the comparatively narrow conductors leading from them. Still another has resided in arcing or short-circuiting arising out of the accumulation between the slip-rings of deposits of finely-divided metal from the slip-rings themselves and of carbon dust from the brushes employed in conjunction with them. Still other defects have resulted from relatively rotary movement between the slip-ring assembly as a whole and the rotor shaft on which it is mounted, such movement creating a condition in which the leads between the rotor and the conductors attached to the slip-rings become severed while the machine is in operation, making for more serious trouble in the machine itself.

It is an object of the present invention to obviate these and other defects by providing a back-ventilated slip-ring assembly of molded construc-

2

tion so designed as to prevent the development therein of temperatures high enough to lead to break-down, such assembly being characterized, among other things, by the fact that the conductors leading from the slip-rings are of massive proportions, are bonded directly to the inside of the slip-rings, and are embedded in the material of which the core itself is formed. It is a further object of the invention to provide a slip-ring assembly which can be made up simply and inexpensively, which requires a minimum of finishing operations, and which lends itself to use as a replacement for existing assemblies in dynamo-electric machines having slip-ring assemblies of other design. It is a further object of the invention to provide a dynamo electric machine characterized by a slip-ring assembly making provision for the effective transmittal of air between the outboard end of the rotor and the interior of the machine.

Other objects and advantages of the invention will be apparent from the description which follows and from the accompanying drawings, in which Figure 1 is an end elevation of the improved slip-ring assembly of the present invention as seen from the rotor; i.e., the interior of the dynamo electric machine. Figure 2 is a longitudinal section, with parts in elevation, along line 2—2 of Figure 1, looking in the direction of the arrows. Figure 3 is a composite longitudinal section, with parts in elevation, along line 3—3 of Figure 1, looking in the direction of the arrows. Figure 4 is a side elevation of the improved slip-ring assembly of the present invention as seen from line 4—4 of Figure 1.

As indicated in Figure 1, the improved slip-ring assembly of the present invention consists, among other things, of an outer sleeve-like annulus in which are positioned the slip ("collecting") rings, of which there may be of from two to four or more but usually three; an inner sleeve-like annulus spaced from the outer annulus by a plurality of arcuate passages extending longitudinally from one end of the assembly to the other; and a plurality of relatively wide webs, corresponding in number to the number of arcuate passages, which are integral with and interconnect the inner and outer annuli. Embedded throughout practically their entire lengths in the material of which the core is molded and located in the webs is a series of conductors leading from and corresponding in number to the number of slip-rings, each of such conductors taking the form of a generally L-shaped stud of massive proportions which is threaded toward

the outer end of its long shank and, at the outer end of its short shank, is bonded by a metallic bond to one of the slip-rings. The entire assembly is mounted by a key and key-way on the rotor shaft and, when so mounted, presents externally the appearance generally suggested by Figure 4.

Referring again to Figure 1, major elements of the improved slip-ring assembly of the present invention thus include the outer sleeve-like annulus 1, the inner sleeve-like annulus 2, a series of relatively wide webs 3, 4 and 5, and, separating the webs, a series of arcuate passages 6, 7 and 8. Like webs 3, 4 and 5, the latter are substantially co-extensive as to length with inner and outer annuli 1 and 2. Within inner annulus 2 is a longitudinally extending center opening 9 receiving the usual rotor shaft; such opening is provided with a lateral extension 10 of the nature of a key-way by which, in known fashion, the slip-ring assembly can be mounted on the rotor shaft. If, in a case in which the assembly is used for replacement, a small diameter shaft is encountered, a metal sleeve may be mounted on the shaft and the slip-ring assembly mounted on the sleeve.

Referring now to Figures 2, 3 and 4, other major elements include slip-rings 15, 16 and 17, which are positioned in spaced relation to each other in the periphery of outer annulus 1. Such slip-rings are in intimate contact with the material of which the core is molded and are held in place, among other things, by gripping action of such material on the knurled surfaces 18, 19 and 20 which characterize the inside of slip-rings 15, 16 and 17 respectively. To each of the three slip-rings is attached a conductor, which, as previously stated, takes the form of an L-shaped stud of massive proportions; such studs are necessarily of different lengths as a result of the fact that slip-rings 15, 16 and 17 are located at different distances from the inboard end of the slip-ring assembly. Slip-ring 15, which is nearest the inboard end of the assembly, requires the shortest stud, such stud, shown in Figure 3, being designated 21; slip-ring 16 requires a stud of intermediate length, designated 22, which stud appears in Figure 2; slip-ring 17, located farthest from the inboard end of the assembly, requires the longest stud, designated 23, which appears in Figure 3.

Except where the short shanks thereof extend toward and are bonded to the several slip-rings, studs 21, 22 and 23 extend in a direction generally parallel to the longitudinal axis of the slip-ring assembly. Each stud is provided at the free or inboard end thereof with a threaded portion 21a, 22a or 23a, to which, as shown in Figure 4, leads are connected in the usual manner. Studs 21, 22 and 23 are located in webs 3, 4 and 5, being disposed approximately mid-way between the inner surface of inner annulus 2 and the outer surface of outer annulus 1. Webs 3, 4 and 5 are somewhat longer, perhaps twice as long, in a circumferential direction than in the radial direction, this in order that studs 21, 22 and 23 may, in so far as possible, be spaced by substantial distances from the surfaces of the slip-ring assembly.

As shown toward the top of Figure 2 and near the bottom of Figure 3, the nearest such surfaces are formed by the deep channels between adjacent slip-rings extending inward into the body of outer annulus 1 to provide a place for the deposition of debris; viz., metallic particles from the slip-rings and carbon dust from the brushes. Such chan-

nels, designated 30 and 31, are located respectively between slip-rings 15 and 16 and between slip-rings 16 and 17; at the base thereof, a sufficient quantity of the material of which the core is formed overlies the stud or studs passing in proximity thereto to preclude the possibility of electrical discharges by way of channels 30 and 31. Other surfaces are formed by the arcuate passages 6, 7 and 8 between adjacent webs; for example, between webs 3 and 4 is the generally arcuate passage 6 having rounded corners which give a blade-like aspect to the radially extending outer walls of webs 3 and 4.

As indicated, outer annulus 1, inner annulus 2 and webs 3, 4 and 5 are integral, being formed simultaneously by a molding operation accomplished by injecting a suitable molding compound into a mold in the manner hereinafter described. When the operation of molding the slip-ring assembly has been completed, such molding compound is in intimate contact over the relatively large surface area thereof with each of studs 21, 22 and 23 and, at the inboard ends of the studs, in contact also with the innermost threads of threaded portions 21a, 22a and 23a thereof. Over most of the inside surface of slip-rings 15, 16 and 17; that is to say, knurled areas 18, 19 and 20, the molding compound of which the core is formed is in intimate contact with the slip-rings.

In addition, the molding compound is preferably carried up around the outer edges of the two end rings, 15 and 17 to provide circumferentially extending shoulders 33 and 34 which help retain rings 15 and 17 in place. Running radially through the core at some convenient point at the base of channel 31 is a threaded bore 35 through which a set screw (not shown) may be applied to the rotor shaft to preclude end-wise displacement of the slip-ring assembly.

In forming the core, it is convenient to use the base of the mold as a stud-carrying fixture, inserting in holes suitably located therein the threaded ends 21a, 22a and 23a of studs 21, 22 and 23. To the opposite ends of the studs will in the meanwhile have been attached slip-rings 15, 16 and 17, the latter being formed by cutting tubular stock into sections. Before cutting, the stock is knurled interiorly to provide knurled surfaces 18, 19 and 20. When the rings have been severed from the stock, studs 21, 22 and 23 are bonded thereto with silver solder at a temperature of 1200 to 1400 degrees F., usually about 1300 degrees F. Thus when studs 21, 22 and 23 are located as described with threaded portions 21a, 22a and 23a thereof in suitable holes in the base of the mold, slip-rings 15, 16 and 17 will form a stack the elements of which lend themselves to easy alignment incident to assembly of the mold.

Mounted on or otherwise associated with the stud-carrying base of the mold will be three tapered inserts, arcuate in cross section, extending from the base of the mold to a point short of the medial plane of the completed assembly. Such inserts are for the purpose of forming arcuate cavities in the assembly, one such cavity, designated 7a, being indicated at the left in Figure 2. A series of like inserts is associated with the side or end walls of the mold, being adapted to leave cavities (such as that designated 7b) in alignment with the cavities formed by the inserts on the mold base. In both instances, the inserts are tapered, the taper being such that the opening left by the insert is greater at the outer end of the assembly than near the medial plane. Between the two sets of inserts will be a clearance

of from $\frac{1}{2}$ to $\frac{1}{8}$ of an inch, provided to preclude interference between oppositely extending inserts.

With studs 21, 22 and 23 mounted as described in the base of the mold and with slip-rings 15, 16 and 17 in substantial alignment, the side and end walls of the mold are next brought into apposition to the stack. The side walls of the mold will ordinarily be equipped with internally projecting ridges for forming channels 30 and 31; being rounded in contour, such ridges slip easily into place between adjacent slip-rings and facilitate closing the walls of the mold around the stack by positioning the slip-rings in proper relation to each other. Preferably, but not necessarily, the mold includes two semi-circular side walls which are forced together and clamped in place to form the mold cavity. At the center of the mold will, of course, be a suitably shaped insert making provision for center opening 9 and key-way 10. The latter will preferably be tapered slightly, being larger at the outboard than at the inboard end of the assembly so as to facilitate removal of the insert from the assembly.

With the studs and slip-rings located as described, with the various inserts in position, and with the side and end walls of the mold in place, a suitable molding compound may be injected into the mold and cured therein under heat and pressure. Preferably, but not necessarily, a fiber-reinforced phenolic molding compound such as fiber-reinforced Bakelite is employed. The fibrous reinforcement may take the form of textile fibers of staple length, glass fibers, asbestos, macerated textile fabrics, etc., all of which may be introduced into the mold with the molding compound. If, as may be desired, sheets of textile fabric, woven glass fabric or like material are to be included as reinforcements in the core of which the assembly is formed, it will of course be necessary that such be introduced and located in position before the mold is closed. Generally speaking, however, it will be sufficient if a powdered molding compound containing loose fibrous reinforcing material is introduced into the mold. Curing takes place at conventional temperatures and pressures but requires a somewhat shorter period of time by virtue of the fact that presence of studs 21, 22 and 23 and the several inserts reduces the maximum effective thickness of the core.

If desired, a metal sleeve (not shown) may be molded in place in the assembly immediately adjacent the inner surface of inner annulus 2.

When curing has been completed, the assembly may be removed from the mold and prepared for finishing. The preliminary operations include the removal of surface flash, punching out of the flash 40 (indicated in dotted lines in Figure 2) formed between opposing arcuate inserts, and, if necessary, machining central opening 9. When these operations have been performed, establishing thereby an accurate center for the assembly, a skin cut is taken off rings 15, 16 and 17 to correct for possible misalignment. By machining rings 15, 16 and 17 together, their external surfaces will be in alignment, thereby minimizing the likelihood of "jumping" of the brushes when the assembly is employed in a dynamoelectric machine. Such other finishing operations as may be desirable are performed at this stage.

When it is desired to install the assembly on the rotor shaft of a dynamoelectric machine, the key 41 (indicated in dotted lines in Figure 2) is

located in place in the key-way of the rotor shaft and the rotor assembly eased into position with key-way 10 in alignment with key 41. Since the central opening 9 will be slightly larger at the outboard end of the assembly than at the inboard end, the key will seat itself somewhat to the left of center as suggested in Figure 2. This having been done, a set screw is introduced through bore 35, after which the open end of bore 35 overlying the end of the set screw is sealed with some suitable sealing compound 42. The leads 43, 44 and 45 to the rotor are then made fast to threaded portions 21a, 22a and 23a, after the slip-ring assembly is ready for operation.

In use, arcuate passages 6, 7 and 8 serve to promote movement of air between the interior of the machine and the outboard end of the slip-ring assembly, thereby increasing the capacity of the rings. The normal direction of movement will be from the outboard end of the assembly toward the interior of the machine, although in special circumstances, depending in part on the construction of the housing, the direction of air movement may be reversed so that air is transmitted from the interior of the machine toward the outboard end of the assembly. In either case, the effect is to reduce very substantially the operating temperature at which the assembly runs. Lacking passages of the nature of arcuate passages 6, 7 and 8, a temperature of about 400° F. is likely to be developed at 3600 R. P. M.; with such passages provided, the assembly can be expected to operate at a temperature below about 300° F. One important result is to delay or preclude breakdown; another, to preclude the likelihood, present in certain of the prior art devices, of separation of parts making up the complete assembly.

It is apparent that numerous modifications may be made without departing from the spirit of the invention; for example, in lieu of a phenolic molding compound, any other natural or synthetic compound lending itself to the desired end may be employed. Ordinarily, slip-rings 15, 16 and 17, as well as the studs connected to them, will be of red brass, although various other metals, such as bronze, may be employed instead. The shape of passages 6, 7 and 8 need not necessarily be arcuate nor need the corners be rounded, although, as indicated, rounded corners contribute to the blade-like aspect of the radially extending outer walls of webs 3, 4 and 5. The number of slip-rings may vary from two to four or more, although three slip-rings are usually present in the ordinary poly-phase dynamoelectric machine. Other changes may readily be made by those skilled in the arts to which the invention pertains.

It is intended that the patent shall cover, by suitable expression in the appended claims, whatever features of patentable novelty reside in the invention.

I claim:

1. In a dynamoelectric machine, a molded slip-ring assembly adapted to transmit air between the outboard end of the rotor and the interior of the machine comprising a sleeve-like outer annulus having on its exterior surface a plurality of collector rings separated by channels extending deep into the body of the outer annulus, the inner faces of said rings having their surfaces roughened to enhance the grip between the rings and the outer annulus; a sleeve-like inner annulus spaced from the outer annulus by a plurality of arcuate passages extending from one end of the assembly to the other; a plurality of rela-

tively wide webs, not less in number than the number of arcuate passages, integral with and interconnecting the outer annulus and the inner annulus, said webs and said annuli being substantially co-extensive in length; and, embedded throughout practically all of the lengths thereof in the material of which the assembly is molded and spaced by virtue of the width of the webs by substantial distances from the surfaces of the slip-ring assembly, a plurality of massively formed studs located in said webs, said studs being L-shaped and having the end faces of the short legs thereof held by metallic bonds to the roughened faces of the collector rings.

2. A molded slip-ring assembly for a dynamo-electric machine comprising an outer annulus having on its exterior surface a plurality of collector rings separated by channels extending deep into the body of the outer annulus, the inner faces of said rings having their surfaces roughened to enhance the grip between the rings and the outer annulus; an inner annulus spaced from the outer annulus by a plurality of passages extending from one end of the assembly to the other; a plurality of relatively wide webs, not less in number than the number of passages, integral with and interconnecting the outer annulus and the inner annulus; and, located in said webs, a plurality of massively formed studs embedded throughout practically all of the lengths thereof in the material of which the assembly is molded and spaced by virtue of the width of the webs by substantial distances from the surfaces of the slip-ring assembly, said studs being L-shaped and having the end faces of the short legs thereof held by metallic bonds to the roughened faces of the collector rings.

3. A molded slip-ring assembly for a dynamo-electric machine comprising an outer annulus having on its exterior surface a plurality of collector rings separated by channels, the inner faces of said rings having their surfaces roughened to enhance the grip between the rings and the outer annulus; an inner annulus spaced from the outer annulus by a plurality of passages extending from one end of the assembly to the other; a plurality of relatively wide webs, not less in number than the number of passages, integral with and interconnecting the outer annulus and the inner annulus; and, located in said webs, a plurality of massively formed studs embedded throughout practically all of the lengths thereof in the material of which the assembly is molded and spaced by virtue of the width of the webs by substantial distances from the surfaces of the slip-ring assembly, said studs being L-shaped and having the end faces of the short legs thereof held by metallic bonds to the roughened faces of the collector rings.

4. A molded slip-ring assembly for a dynamo-electric machine comprising an outer annulus having on its exterior surface a plurality of collector rings, the inner faces of said rings having their surfaces roughened to enhance the grip between the rings and the outer annulus; an inner annulus spaced from the outer annulus by a plurality of passages extending from one end

of the assembly to the other; a plurality of relatively wide webs integral with and interconnecting the outer annulus and the inner annulus; and, located in said webs, a plurality of massively formed studs embedded in the material of which the assembly is molded and spaced by virtue of the width of the webs by substantial distances from the surfaces of the slip-ring assembly, said studs being L-shaped and having the end faces of the short legs thereof held by metallic bonds to the roughened faces of the collector rings.

5. A molded slip-ring assembly for a dynamo-electric machine comprising an outer annulus having on its exterior surface a plurality of collector rings, the inner faces of said rings having their surfaces roughened to enhance the grip between the rings and the outer annulus; an inner annulus spaced from the outer annulus by a plurality of passages extending from one end of the assembly to the other; a plurality of relatively wide webs integral with and interconnecting the outer annulus and the inner annulus; and, located in said webs, a plurality of massively formed studs spaced by virtue of the width of the webs by substantial distances from the surfaces of the slip-ring assembly, said studs being L-shaped and having the end faces of the short legs thereof held by metallic bonds to the roughened faces of the collector rings.

6. A molded slip-ring assembly for a dynamo-electric machine comprising an outer annulus having on its exterior surface a plurality of collector rings, the inner faces of said rings having their surfaces roughened to enhance the grip between the rings and the outer annulus; an inner annulus spaced from the outer annulus by a plurality of passages extending from one end of the assembly to the other; a plurality of relatively wide webs integral with and interconnecting the outer annulus and the inner annulus; and, located in said webs, a plurality of studs spaced by virtue of the width of the webs by substantial distances from the surfaces of the slip-ring assembly, said studs being L-shaped and having the end faces of the short legs thereof held by metallic bonds to the roughened faces of the collector rings.
